Primary Examiner — Patricia A Palasik(74) *Attorney, Agent, or Firm* — PATENTFILE, LLC; Bradley C. Fach; Steven R. Kick(57) **CLAIM**

The ornamental design for a panel light, as shown and described.

DESCRIPTION

FIG. 1 is a top perspective view of a panel light, showing my new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof;

FIG. 7. is a bottom plan view thereof; and,

FIG. 8 is a bottom perspective view thereof.

The broken lines in the drawings are for the purpose of illustrating portions of the panel light which form no part of the claimed design.

1 Claim, 5 Drawing Sheets(56)
